UNITED STATES PATENT OFFICE.

EDMUND W. TAYLOR, JR., OF BROOKLYN, NEW YORK.

DESIGN FOR BOX-PLAITED RUFFLES.

Specification forming part of Design No. 6,191, dated October 8, 1872.

To all whom it may concern:

Be it known that I, EDMUND W. TAYLOR, Jr., of Brooklyn, in the county of Kings and State of New York, have invented a new and original Design for Box-Plaited Ruffles, of which the following is a specification:

The accompanying photograph illustrates my invention:

The design relates to the arrangement on box-plaited ruffles of stitching at the edges and at the middle—it having been heretofore the custom to make box-plaited ruffles without stitching. Thread of any preferred color may be employed in forming the stitches. The appearance of the ruffle by the application of the stitching is greatly improved.

I claim as my invention—

The design for a box-plaited ruffle, stitched at the edges and the middle, as shown.
